UNITED STATES PATENT OFFICE.

SAMUEL AUGUSTINE DE NORMANVILLE, OF EALING, AND LESLIE HARCOURT KENT,
OF STANMORE, ENGLAND.

VISUAL WEATHER-SCREEN.

1,297,805.

Specification of Letters Patent. Patented Mar. 18, 1919.

Application filed May 8, 1917. Serial No. 167,381.

To all whom it may concern:

Be it known that we, SAMUEL AUGUSTINE DE NORMANVILLE and LESLIE HARCOURT KENT, both subjects of the King of Great Britain, residing at Ealing, Middlesex, England, and Stanmore, Middlesex, England, respectively, have invented certain new and useful Improvements in Visual Weather-Screens, of which the following is a specification.

This invention relates to improvements in visual weather screens in which a transparent disk is rotated so that rain and spray driving against it are thrown off under centrifugal action.

The invention comprehends means for mounting the disk and means for driving it by which it may be rotated at a speed sufficiently high to insure complete transparency being maintained without the aid of wiping devices such as have hitherto been necessary with a slowly rotating disk.

To meet these conditions the disk must be mounted in a firm support but the support and the driving mechanism should be such as to offer the minimum obstruction to the sight of the observer.

The invention also comprises details hereinafter referred to for increasing the efficiency of the screen and for facilitating its use.

In the drawings:

Figure 1 is a side sectional elevation of one form of screen according to the invention applied to a look-out suitable for use on a ship or in a similarly exposed position.

Fig. 2 is a detail view of a universal joint.

Figs. 3 and 4 are detail sectional views illustrating different forms of rims for the disks.

In one form of the invention as illustrated by Fig. 1, the hood 1 or shelter is revolvably mounted on a pedestal 2. The hood 1 is closed in front but open at the back and has a bottom or table 3, for the observer to lean upon with his head and shoulders in shelter. Through the bottom of the hood passes a sleeve 4 firmly clamped to it by a ring nut 5. This sleeve 4, carrying the hood, is passed over the top of the pedestal 2. In order to allow for adjustment in height, the sleeve 4 is internally threaded for part of its length and engages with a threaded head 6 on the top of the pedestal 2 so that when the hood 55 is revolved continuously the hood will rise

or fall. The hood may be fixed or locked, when not required for use, by a locking screw 7 provided on the lower plain part 8 of the sleeve 4 which is preferably a sliding fit on a corresponding part 9 of the pedestal 2.

The glass disk 10 is mounted to run within a circular ring or housing 11 having a bracket or radial arm 12 preferably cast in one with it, which carries a central bearing 13 through which the disk spindle 14 passes. The disk 10 is clamped between two nuts 15 on the spindle. These parts form a unit which is fixed into an opening in the front of the hood 1 and which is easily removable for repair or adjustment.

In the form shown in Fig. 1 the disk 10 is clamped on the spindle 14 so as to rotate therewith.

The driving of the disk 10 is effected by a motor preferably an electric motor 16 arranged within the pedestal 2. It drives a vertical shaft 17 passing up centrally through the pedestal and sleeve 4 into the hood 1, and provided with a sliding joint or coupling 18 to allow for the rise and fall of the hood. The shaft is connected, at its upper end, to the spindle 14 of the disk 10 by means of a short shaft or link 19 at an angle of about 45° and two Hook's couplings or similar universal joints 20, one at each bend. A suitable universal joint is shown in Fig. 2 and comprises a square block 21 drilled with four holes at right angles meeting at the center and receiving four pins 22 screwed in pairs into two forks 23, all lubricated from the center of the block by a single grease cup 24 occupying one of its vacant sides. The link is provided with a sliding joint 25 for automatic adjustment in length and ease in assembling and dismounting.

The driving shaft may pass through a packing gland 26 on the top of the sleeve 4.

The rheostat 29 for the motor 16 and of usual construction may be arranged on the inside of the door 30 giving access to the motor, a central knob 31 on the door actuating the rheostat from outside.

The peripheral edge of the disk may be beveled and may run in close proximity to a corresponding bevel on the circular ring or housing 11, clearance being adjusted by means of the nuts 15 above described. Or such bevel may be formed on a metal ring 32, Fig. 3, spun or clamped on to the disk 10 to strengthen it.

In another form the disk 10 has a projecting cylindrical rim 33, Fig. 4, adapted to run over a similar fixed rim or flange 34 on the frame 11.

5 By passing the driving shaft into the hood through the axis of rotation of the latter, movements of the hood do not interfere with the driving gear.

We claim:—

- 10 1. In look-out apparatus, a hollow substantially vertical pedestal having its upper end screw threaded, a sleeve rotatable upon the upper portion of the pedestal and having screw threaded engagement therewith 15 to be raised and lowered upon the rotation of the sleeve, means to lock the sleeve to the pedestal against rotation with relation thereto, a hood rigidly secured to the sleeve and having a forward side provided with an 20 opening, a rotatable transparent element spanning the opening, a substantially vertical shaft arranged within the upper portion of the hollow pedestal, means to gear the upper end of the shaft with the rotatable 25 transparent element, a motor arranged in the lower portion of the hollow pedestal, and self adjusting extensible connecting means between the motor and said shaft.
2. In look-out apparatus, a hollow substantially vertical pedestal, a sleeve rotatably mounted upon the upper portion of the pedestal, a hood rigidly secured to the sleeve and having a forward side provided with an opening, a bearing arranged substantially centrally of the opening and having an arm secured to the hood and entirely supported thereby, a spindle rotatable within the bearing, a transparent element spanning said opening and secured to the 35 spindle to be rotated thereby, a drive shaft extending longitudinally within and through the substantially vertical hollow spindle, and driving connecting means between the upper end of the drive shaft and the spindle.
- 40 3. In look-out apparatus, a hollow substantially vertical pedestal, a sleeve rotatably mounted upon the upper portion of the pedestal, a hood provided in its bottom with an opening to receive the sleeve and
- 45

having its forward side provided with a 50 look-out opening, means to clamp said bottom to the sleeve, a drive shaft extending longitudinally through the hollow pedestal and sleeve, a ring arranged within the look-out opening and secured to the forward side 55 of the hood, a radially disposed arm rigidly secured to the ring and projecting inwardly therefrom with its inner end disposed near the center of the look-out opening, a bearing carried by the inner end of said arm, a spindle journaled within the bearing, a rotatable transparent element operating within the ring and secured to the spindle, and driving connecting means between the spindle and the upper end of the drive shaft. 60

4. In look-out apparatus, a hollow substantially vertical pedestal, a sleeve rotatably mounted upon the upper portion of the pedestal, a hood rigidly secured to the sleeve and having a forward side provided 70 with an opening, the walls of which is beveled outwardly, a bearing arranged substantially centrally of the opening and having an arm secured to the hood and entirely supported thereby, a spindle rotatable within 75 the bearing, a frame carrying a transparent element spanning said opening and secured to the spindle to be rotated thereby, the frame being beveled on its outer edge to correspond with the beveled wall of the 80 opening, a drive shaft extending longitudinally within and through the substantially vertical hollow spindle, and driving connecting means between the upper end of the drive shaft and the spindle. 85

In testimony whereof we have signed our names to this specification in the presence of two subscribing witnesses.
